UNITED STATES PATENT OFFICE.

FRANK E. CASE, OF SCHENECTADY, NEW YORK, ASSIGNOR TO GENERAL ELECTRIC COMPANY, A CORPORATION OF NEW YORK.

ELECTRIC CONTROLLER.

SPECIFICATION forming part of Letters Patent No. 697,132, dated April 8, 1902.

Application filed July 16, 1900. Serial No. 23,711. (No model.)

To all whom it may concern:

Be it known that I, FRANK E. CASE, a citizen of the United States, residing at Schenectady, county of Schenectady, State of New York, have invented certain new and useful Improvements in Electric Controllers, (Case No. 1,163,) of which the following is a specification.

My invention relates to a magnetic blow-out device for electric controllers, and has for its object to provide an improved arrangement of the chute structure, in which the arcs are disrupted.

In my prior application, Serial No. 671,994, I have described and claimed a new form of blow-out device in which the magnetic field has a direction substantially at right angles to the direction of motion of the moving contacts and perpendicular to the face along which contact is made and in which the chutes are so arranged that the arc is restrained in its movement in the direction in which it tends to move in the magnetic field and is compelled to expand sidewise in flattened loops until it is disrupted.

My present invention comprises a modified form of the above invention as applied to a controller of the type in which the movable contacts are mounted on a common support.

It also comprises certain details of construction applicable to switches in general.

My invention will be more clearly understood by reference to the following specification, taken in connection with the accompanying drawings, while its scope will be clearly pointed out in the appended claims.

In the drawings, Figure 1 illustrates a controller provided with an arc chute structure arranged according to my invention. Fig. 2 is a cross-section along the line 2-2 of Fig. 1. Fig. 3 is a perspective view showing more in detail the construction of the chutes in which the arcs are disrupted; and Fig. 4 is a detail sectional view of one of the blow-out chambers, showing the position of the stationary and movable contacts of the controller with respect thereto.

Referring to Fig. 1, which shows my invention as applied to a controller having two main cylinders, A illustrates the controller-

casing; C' and C², the main controller-cylinders; C³, the reversing-switch cylinder, and M the blow-out magnet. The fixed contacts for the controller-cylinders are mounted on the insulating-supports d' and d², extending 55 along the length of the controller-casing.

The arrangement thus far described constitutes no part of my invention.

My invention relates to the structure B, containing the chambers in which the arcs are 60 formed and disrupted at the time that the circuit is broken at the controller-contacts. In the particular controller chosen for illustration this structure comprises two sets of chutes of similar construction, one for each 65 of the main cylinders, and is supported on hinges e and f at one side of the controller, so that it may be readily swung aside to expose the controller-contacts to view. It is held in the closed position by a bolt screwing 70 into the core of the blow-out magnet. On the outside of the two sets of chutes and positioned directly over the fixed contacts of the controller lie the bars of the magnetic material g' and g², constituting one pole of the 75 blow-out magnet. These strips are united to each other at g³ and g⁴ and are connected to the core on which the coil M is wound by means of the portions g⁵ and g⁶.

The construction of the chutes is shown 80 more clearly in Fig. 3, which represents in perspective a portion of the chute structure for the contacts of the cylinder C'. In the upper portion of this figure, which is shown partially in outline, with the front broken away 85 in order that the interior construction may be rendered clear, l and l' represent the fingers supporting two of the fixed contacts of the controller. The coöperating movable contacts are mounted on the surface of the cylinder, two of such contacts being shown at m and m'.

Each of the fixed contacts is mounted in an arcing-chamber, which has its upper and lower walls provided with openings adjacent 95 to the fixed contact and its side walls cut away to leave room for the contact-fingers and to permit the rotation of the cylinder-contacts. Adjacent to each of the arcing-chambers above and below is arranged a second cham- 100

ber, which I have termed a "blow-out" chamber, this chamber having an opening into the arcing-chamber at the point adjacent to the controller-contacts and being otherwise closed, except for two openings in the front wall at points removed from the opening into the arcing-chamber.

As shown in the drawings, all the chutes are comprised in a common structure built of 10 any suitable refractory insulating material. The angularly-arranged strips b' and b^2 constitute the sides of the chutes. Between these side pieces are mounted the wedge-shaped strips h' and h^2 , constituting the upper and 15 lower walls of the arcing and blow-out chambers. Each of the strips h' is provided with an opening adjacent to the fixed contacts, and each of the strips h^2 is solid. A strip i , interposed between the strips h' and h^2 , 20 completely incloses the back side of the blow-out chamber formed between the plates h' and h^2 . On the front the edges of all the strips lie in the same plane, and the sheet k , fastened to these edges, closes the front side of both the arcing 25 and the blow-out chambers. The part k is provided with apertures k' at each side of each of the blow-out chambers, but it closes completely the front side of the arcing-chamber.

As shown in the drawings, a blow-out chamber is provided on each side of each of the arcing-chambers. This construction is rendered necessary in the particular controller chosen for illustration by reason of the fact that in different positions of the controller the 30 current flows in different directions through the controller-contacts, so that at certain times the arc is propelled upward and at other times downward. As is well known, an arc when in a magnetic field tends to travel in a 35 direction at right angles to the direction of the lines of force. In the construction shown in the drawings the arc will travel either up or down, according to the direction of current-flow, for the magnetic field has a direction 40 substantially at right angles to the direction of motion of the moving contacts and substantially perpendicular to the face along which contact is made.

The manner in which the arc is extended 45 and finally broken is indicated in Fig. 4. As shown in this figure, the flow of current is in such a direction that the arc tends to travel downward until it reaches the edge of the contacts. Thereafter the arc is stretched, as 50 shown in the dotted lines, until it extends through the opening in the wall h' and impinges against the lower wall h^2 of the blow-out chamber. The wall h' prevents the spreading of the arc along the length of fingers and contacts. The progress of the arc 55 in the direction in which it tends to travel is limited by its contact with the wall h^2 ; but the arc being still within the influence of the magnetic field it is expanded in flattened 60 loops extending lengthwise of the chamber until finally it is disrupted. By this arrangement it will be seen that the arc is first

blown for a certain distance in a direction at right angles to the direction of the lines of force away from the upper or lower edge of 70 the contacts until it impinges against the end wall of the blow-out chamber, and then, by reason of the restrictions afforded by the said end wall, it is blown in two directions from the central point in a plane substantially 75 parallel to the direction of movement of the moving contacts of the controller.

What I claim as new, and desire to secure by Letters Patent of the United States, is—

1. In combination, in an electric controller 80 provided with a series of movable contacts mounted on a common support and a series of fixed contacts adapted to engage therewith, means for producing a magnetic field in a direction substantially at right angles to the 85 direction of motion of the moving contacts and substantially perpendicular to the face along which contact is made, a blow-out chamber adjacent to each of said fixed contacts, said chamber having an opening adjacent to 90 the contacts for the reception of the arc, and a closed wall opposite to said opening in the direction of travel of the arc.

2. In combination, in an electric controller 95 provided with a series of movable contacts mounted on a common support and a series of fixed contacts adapted to engage therewith, means for producing a magnetic field in a direction substantially at right angles to the 100 direction of motion of the moving contacts and substantially perpendicular to the face along which contact is made, an arcing-chamber inclosing each set of contacts, and a blow-out chamber adjacent to each arcing-chamber, said blow-out chamber communicating 105 with the arcing-chamber through an opening adjacent to the contacts and having a closed wall opposite to said opening.

3. In combination, in an electric controller, 110 a rotatable cylinder provided with contacts, a plurality of fixed contacts adjacent thereto, means for producing a magnetic field in a direction substantially at right angles to the 115 direction of motion of the moving contacts and substantially perpendicular to the face along which contact is made, and a chute structure comprising arcing-chambers inclosing the contacts, and blow-out chambers adjacent thereto, each of said arcing-chambers 120 having portions of the walls cut away to permit the rotation of the contacts and each of the blow-out chambers communicating with an arcing-chamber through an opening adjacent to the contacts and with the atmosphere at a point or points laterally displaced therefrom. 125

4. In combination, in a cylindrical controller, means for producing a magnetic field in a direction substantially at right angles to the 130 direction of motion of the contacts and substantially perpendicular to the face along which contact is made, and a chute structure comprising blow-out chambers adjacent to each set of contacts, each of said blow-out chambers having an opening adjacent to the

controller-contacts and a closed wall opposite thereto in the direction in which the arc tends to travel.

- 5 5. In combination in an electric switch, means for producing a magnetic field in a direction substantially at right angles to the direction of motion of the moving contacts, an arcing-chamber inclosing the switch-contacts, and blow-out chambers on each side of 10 said arcing-chamber, said blow-out chambers communicating with the arcing - chamber through openings adjacent to the contacts and having closed walls opposite to said openings in the direction of travel of the arc.
- 15 6. In combination in an electric switch,

fixed and movable contacts, means for producing a magnetic field in a direction substantially at right angles to the direction of motion of the moving contacts, and blow-out chambers on each side of said contacts, each 20 of said chambers being provided with an opening adjacent to the contacts for the reception of the arc, and having a closed wall opposite to said opening.

In witness whereof I have hereunto set my 25 hand this 13th day of July, 1900.

FRANK E. CASE.
